(No Model.)

A. E. BEARRIE.
TAILOR'S SQUARE.

No. 350,104

Patented Oct. 5, 1886.

UNITED STATES PATENT OFFICE.

ARTHUR E. BEARRIE, OF CHICAGO, ILLINOIS.

TAILOR'S SQUARE.

SPECIFICATION forming part of Letters Patent No. 350,104, dated October 5, 1886.

Application filed April 13, 1886. Serial No. 198,675. (No model.)

To all whom it may concern:

Be it known that I, ARTHUR E. BEARRIE, of Chicago, in the county of Cook and State of Illinois, have invented certain new and useful 5 Improvements in Tailors' Squares, of which the following is a description, reference being had to the accompanying drawings, in which—

Figure 1 is a plan view of my improved square. Fig. 2 is a plan view of the same with the legs closed. Fig. 3 is an edge view showing the devices for holding the legs open.

My invention relates to tailors' squares and measuring devices for use in laying off and cutting garments; and it consists in the construction and combination of parts herein described, and pointed out definitely in the claims.

In the drawings, A represents the long leg, and A' the short leg, of the square. These two legs are pivoted together at *a*. Upon the outer edge of one leg, A', a flat spring, B, is secured, the free end of which projects beyond the leg A' and ends in a beveled catch, *b*. This catch is provided with the slot *b'*. (Shown in Fig. 3.) 25 Upon the corresponding edge of the other leg, A, I bevel the part adjacent to the leg A' to correspond with the beveled catch *b*; and I also provide a beveled stud, *b*², adapted to enter the slot *b'* when the legs are at right angles 30 with each other. A spring-catch is thus formed which, when the legs are swung open, automatically catches and holds the legs at right angles with each other until the spring B is lifted. When a measuring instrument—a 35 rule—only is wanted, the legs are closed, as shown in Fig. 2, which is much more convenient than when the legs are open. When a square is desired, the legs are swung apart, the beveled catch slides upon the beveled stud *b*² 40 until the spring B forces the slot *b'* down over said stud, when the legs A, A' are, as before

explained, retained in a position at right angles to each other.

The two legs of the device may be graduated with any desired unit of measure and in any appropriate manner.

As a further improvement I construct upon the free end of the long arm A the irregular curve C, as shown. This curve begins upon said arm at a point where the short arm A', when closed, will not strike it, but will lie close to the long arm, as shown in Fig. 2. The curve C can thus be used when the device is in its most convenient form—to wit, closed—as shown in Fig. 2, with nearly, if not quite, as great facility as if it were a separate instrument, while the inconvenience of having two tools lying about the work-table is avoided.

Having thus described my invention, what I claim as new, and desire to secure by Letters Patent, is—

1. A tailor's square consisting of two legs pivoted together, combined with a slotted spring-catch secured to one edge of one leg and a beveled stud secured to the corresponding edge of the other leg adapted to automatically enter said slot, substantially as and for the purpose set forth.

2. A tailor's square consisting of two legs pivoted together, the end of one leg being beveled toward its inner edge and having a beveled stud secured to said beveled part, the outer edge of the other leg being provided with a flat spring having a beveled end and a slot through said beveled end, the whole combined and arranged substantially as and for the purpose specified.

ARTHUR E. BEARRIE.
